(57) **CLAIM**

The ornamental design for an earbud case, substantially as shown and described.

DESCRIPTION

FIG. 1 is a perspective view of an earbud case as seen from the top, right side and front;

FIG. 2 is top view thereof;

FIG. 3 is a right side view thereof;

FIG. 4 is a bottom view thereof;

FIG. 5 is a left side view thereof;

FIG. 6 is a front view thereof; and,

FIG. 7 is a back view thereof.

The broken lines shown in the drawings depict portions of the earbud case that form no part of the claimed design.
